REFRESHMENT STAND

Peter J. Rollo, Matawan, N. J.

Application January 12, 1950, Serial No. 7,188

Term of patent 14 years

(Cl. D13—1)

To all whom it may concern:

Be it known that I, Peter J. Rollo, a citizen of the United States, residing at Matawan, State of New Jersey, have invented a new, original, and ornamental Design for a Refreshment Stand, of which the following is a specification, reference being had to the accompanying drawing, forming a part hereof.

Fig. 1 is a plan view of a refreshment stand embodying my new design;

Fig. 2 is a front elevational view of the refreshment stand shown in Fig. 1; and

Fig. 3 is a sectional view through the stand shown in Fig. 1 and taken on the line 3—3.

I claim:

The ornamental design for a refreshment stand, as shown.

PETER J. ROLLO.
